UNITED STATES PATENT OFFICE

ALBERT H. ONSTAD, OF TACOMA, WASHINGTON, ASSIGNOR TO WEYERHAEUSER TIMBER COMPANY, OF TACOMA, WASHINGTON, A CORPORATION OF WASHINGTON

LUMBER RETRIMMING MACHINE

Application filed January 18, 1932. Serial No. 587,198.

My invention relates to a device intended to be disposed in the path through which lumber is carried in operations such as planing and grading, or in any like operation, by means of which device the lumber in its passage has the two ends of each board trimmed square across and a definite distance apart, and by means of which, if the mill operator desires, a distinguishing mark may be placed upon the trimmed end of the lumber.

There are a number of reasons why it is desirable to perform these operations. Naturally, it is of advantage to the purchaser to know that the lumber he buys is exact in dimension, and that the ends are precisely squared off rather than left rough and uneven as cut by the original cross-cut saw. From the standpoint of the mill man, it gives the lumber a better and more finished appearance, and creates the impression of freshness which sometimes is marred by old, seasoned ends remaining upon the boards. It enables him to mark each piece with a suitable mark—for instance, a grade mark or a trade-mark—whereby the purchaser may know the source of the lumber and may know the standard mill grading, and cannot be induced to purchase lower grade lumber as of higher grade.

It is the general object, then, to provide a machine which will enable the accomplishment of the above advantages, and, further, to provide a machine for such a purpose which can be so interposed in the path through which the lumber must necessarily travel that the delivery of lumber is little if any impeded, and its handling by hand is not required.

It is an object to devise a trimming and printing machine which is simply and quickly adjustable to receive all sizes of lumber, varying as to width, thickness and length (within reasonable limits), and through which all pieces of the size for which the machine is set can be passed without the necessity of the attention of an operator.

It is an object to provide such a trimming and printing machine having safety or cut-out devices which will control the printing and prevent operation of the printing mech-

anism except when there is a board in position to be printed.

It is an object to provide in such a machine a means which will insure the lifting of the saw from its operative or trimming position prior to the shifting of that saw in adjusting for the trimming of boards of a length different from that which had theretofore been trimmed.

It is an object to provide simple controls for the several adjustments, and to assemble such controls at a single location, so that one operator may make the necessary adjustments from one station, and it is thereby made unnecessary to communicate between operators at different positions, over and above the noise of a planer mill.

It is an object to provide an automatic control so that the machine will not feed lumber through the trimming and printing stations faster than the mechanisms there can handle it, and which will adjust itself automatically to compensate for a slower feed rate.

Many further objects of my invention will become apparent as the description progresses, and all of the various objects of this invention may be achieved by constructions varying from that illustrated in the drawings, which latter construction is at present preferred by me, but it will be understood that my invention is not restricted to the construction shown and described, except as required by limitations in the claims.

In the accompanying drawings, therefore, I have shown my invention embodied in an illustrative form such as is at present preferred by me.

My invention comprises the novel parts, the novel combination thereof, and the novel arrangement of parts relative to one another and to other apparatus, all as is shown in the drawings, described in this specification, and more particularly pointed out by the claims.

Figure 1 is a general plan view of the machine embodying my invention.

Figure 2 is a side elevation of my machine.

Figure 3 is an end elevation thereof looking into the magazine, and Figure 4 is a de-

tail of the magazine showing a slightly modified arrangement of parts.

Figure 5 is an elevation, from the same viewpoint as Figure 3, illustrating the trimming saw and printing mechanism associated therewith.

Figure 6 is an elevation of the same mechanism taken from a viewpoint at right angles to Figure 5 showing the printing mechanism 10 in inoperative position, and Figure 7 is a similar view on a larger scale, showing the printing mechanism in the act of printing.

Figure 8 is a diagrammatic showing a certain safety or stop mechanisms controlling 15 the withholding from operation of the printing mechanism; Figure 9 is a second diagram illustrating the mechanisms of Figure 8 and further control mechanism for the printing devices, and Figure 10 is an elevation 20 of a detail of Figure 9.

Figure 11 is a diagrammatic view of an 25 automatic control governing the starting and stopping of the machine in accordance with the rate at which boards are fed into the machine.

Referring first to Figures 1, 2 and 3, the device essentially comprises an adjustable saw 1 and a fixed saw 10 supported upon suitable frame members (the saw 1 being adjustable axially toward and from the saw 10), a magazine 3 within which lumber is received by endwise movement from any suitable mechanism, typified by the planer P, and from which it is discharged by conveyor 35 chains 7, so that it moves edgewise, the lowermost board of the pile in the magazine being fed out and additional boards being supplied upon the top of the pile. Moved by the conveyor 7 and positioned thereby precisely 40 transversely of the direction of movement, the boards are carried in turn past the saws 1 and 10, which have been adjusted to the precise length to which the lumber is to be trimmed, and the two ends are thereby 45 trimmed off. Thereafter there will usually be employed a printing mechanism indicated generally at 4 and duplicated, if desired, at the opposite end, whereby a suitable mark is 50 imprinted upon the freshly trimmed ends of each board as it passes. The lumber may then be discharged to a grading table, or any other suitable conveyor, typified at G, where it is graded, sorted, or otherwise advanced 55 along its path of movement, ultimately to be piled and shipped.

As has been mentioned, the boards are fed endwise into the magazine 3, and in order to stop the boards so that their trailing ends stop approximately adjacent the entrance end 60 of the magazine, a buffer member 30 is provided at the far end of the magazine, supported upon parallel links 31 from a slide or traveler 32 which is movable along one of the frame members 9 extending transversely of the trimming machine—that is to say, paral-

lel to the length of the board. This buffer member 30 is of considerable weight, and the leading ends of the boards, if they have sufficient momentum, will strike it and deflect it slightly, but will be caused to lose their momentum thereby, and will drop in the magazine. If their momentum has previously been absorbed by friction with the previously fed board beneath the trailing ends, fed forward by the feed devices associated with the planer, and moving from the level P to a lower level within the magazine (depending upon the height to which boards are piled, but to the possible low level of the frame members 90, which extend at right angles to the members 9 and considerably below the same), will drop adjacent the entrance end of the magazine. The saw at this end, then, may be fixed in position, and the opposite saw is adjustable, together with the buffer 30.

The sides of the magazine are determined by the vertical walls 33 and 34, the latter of which at least is adjustable to accommodate boards of different widths. It is also adjustable in height, so that the spacing between 90 its lower edge and the top of the frame members 90, upon which the boards move edge-wise, can be varied to permit the delivery of one board only in each instance, whatever may be the thickness of the boards being run 95 through.

To accomplish adjustment of the magazine for boards of different thickness, the wall 34 is supported by arms 35 having at their upper ends a sleeve 36, by means of which it 100 is hung from a short shaft 83 supported upon the frame members 9. At their lower ends these arms 35 are pivotally connected at 37 to the wall 34, and these arms all being equal, the board is in effect supported by 105 parallel links. Now by swinging these links, the bottom edge of the board may be raised or lowered, and to do this a link 38, connected at one end to the wall 34, is shortened or lengthened by threaded engagement of a rotatable nut 39, supported by an extension 351 on one of the arms 35. Operation of this nut is controlled by a handle 390. The wall 34 is maintained against deflection from its own plane by reason of the employment of a 115 spur 350 which extends beyond the pivot 37 to stiffen and strengthen the wall.

Adjustment of the magazine for width is accomplished by engaging each sleeve 36 between collars 830 fixed on the several shafts 120 83, and by providing means for simultaneously and equally sliding these shafts 83 transversely of the magazine 3. For instance, one end of the shaft may be keyed as indicated at 831, this keyed end being held in a slotted box or guide 832, and an intermediate portion of each shaft is slidable in a guide 833. The end of each shaft opposite the key 831 has rack teeth 834 with which is engaged a rack pinion 835. These pinions are carried 130

upon the longitudinal shaft 836 journaled in suitable bearings 837 carried by one of the frame members 9. Rotation of the shaft 836, by means such as the hand wheel 837, causes simultaneous movement of each of the shafts 83 axially, and thereby effects bodily side-
wise movement of the arm 35 and the magazine wall 34 supported therefrom. Each adjustment, then, transversely or for height, 10 may be accomplished independent of the other adjustment.

Adjustment of the magazine for length is accomplished, as has been indicated, by shifting the buffer member 30. The slide 32 which 15 supports this buffer slides along a flange of one of the frame members 9, as has been indicated, and is controlled for movement lengthwise of this frame member and lengthwise of the magazine 3, by means such as the 20 chain or cable 84 passing over pulleys 840 and 841. The pulley 840 is upon a shaft 842 journaled between frame members 9, upon which is a pulley 843 connecting by a chain or like member 844 to a pulley 845, leading 25 finally to a control shaft 81 with its hand wheel 810. By these or like means the buffer 30 can be drawn toward or moved from the planer P to accommodate boards of different 30 lengths. Naturally, all boards sent through at one time would be approximately the same length, as they would also have to be of the same width and thickness.

Adjustment of the saw 1 to trim boards of different lengths may be accomplished in 35 a manner similar to that described for the buffer 30, and preferably it is controlled by the same means, namely, the shaft 81 and its hand wheel 810. The saw is journaled in a head 120 carried at the lower end of a vertical slide 12. This slide 12 is guided for vertical movement in guides 21 supported from a carriage 2. The carriage is supported upon wheels 20 whereby it may move along tracks 91 supported from adjacent frame members 40 9. Likewise supported upon the carriage 2 is a suitable means of raising the slide 12, 45 illustrative in this instance as the known hydroelectric operator 23. In effect, this is a device enabling the projection of a piston rod or rods 24 under hydraulic pressure generated by electrical means within the member 23, so that a cross head 25 is raised or lowered at will, and controlled by a push button. Controlled by movement of this cross head 50 55 is a rod or rods 22 extending downward to a connection with the vertical slide 12. By such means the head 120 and saw 1 are raised and lowered. A motor 14 for rotating the saw 1 is carried on the head 120.

Lengthwise movement of the carriage 2 60 may be effected by connecting to it a chain or cable 821 running from a pulley or sprocket 822 on the shaft 81 and over a return sprocket or pulley 823 at the opposite end of 65 the machine, this chain or pulley connecting

to the carriage 2. Thus movement of the carriage and of the buffer is controlled by the single shaft 81.

It is essential that movement of these elements be prevented except at the will of the operator. It is also desirable that the lumber be only cut at given intervals of length, so that the different lengths vary by precisely one foot or by precisely six inches, or whatever variation is deemed desirable. Accordingly, in connection with one of the frame members 9 and tracks 91, I may provide a plate 911 which is notched at intervals, as indicated at 912, and to the vertical slide 12 I connect a tapered finger 15 which moves up and down with the vertical slide, this finger 15 being formed to fit into the several notches 912, and when seated in such a notch to hold the carriage 2 against adjustment. When the finger is thus engaged the saw 1 is 85 in operative position with respect to lumber moving over the frame members 90, and since the finger 15 must be withdrawn upwardly to permit adjustment of the saw to a new position, this insures that the saw will be 90 drawn upwardly to clear the frame members 90 and anything which may rest thereon during such adjustment of the saw, for the finger 15 projects downwardly so far that it will only clear the plate 911 when the saw 95 has been thus raised.

The device as thus far explained may be considered complete in itself, and will operate to trim the two ends of lumber as the lumber is advanced by the transverse chains, 100 belts or conveyors 7 extending over the pulleys 70 and 71, and having spaced lugs 72 upstanding above the upper level of the frame members 90 to engage the boards and drag them one by one from beneath the pile 105 in the magazine past the saws 1 and 10. However, it is desirable that there be provided means for printing a mark upon the newly cut ends of the boards, and such printing mechanism can readily be associated and 110 movable with the carriage 2.

The printing die 4 is suitably supported from a slide 40, which may be slidable upon the plate 911 with which the finger 15 cooperates. In order to control movement of the printing device it may be coupled, secured or linked to the carriage 2 or a member which is rigid therewith—for instance, a bolt 42 may be employed to secure together 115 the two.

The printing die is normally held retracted by suitable means, and is actuated by control devices to be projected rapidly forward at such time as it will strike the trimmed end of a board equidistant from its 125 two edges, whereupon it is immediately withdrawn. The striking and withdrawing must be so rapid and positive that, even though the board is traveling transversely to the direction of movement of the printing die, 130

- there is no tendency to drag or blur, nor to strike repeatedly. A combination of mechanical and electrical control means has been found suitable for the purpose. The mechanical means—a spring for instance—may cause the striking action, and the electrical means—magnet or solenoid—may accomplish the withdrawal, or, as shown herein, the reverse may be the case.
- 10 Thus, as illustrated, the printing die 4 is normally held retracted by a spring 41, but is guided for horizontal movement in a guide 400 formed at the lower end of the slide 40. At the end opposite the printing end the die has a cross pin 43 with which is engageable an arm 44 carrying an armature 441. The arm 44 is pivoted at 440; supported in position to attract the armature 441 is an electromagnet 45.
- 15 An ink pad 46 is supported by links 47 and 48, the one upon the member 40 and the other connected to the slidable die 4, so that upon projection of the printing die 4 to the left, as seen in Figures 6 and 7, the ink pad 46 will be raised from its path to permit it to print upon the board, as seen in Figure 7, and immediately upon retraction of the printing die under the influence of the spring 41 (the current to the magnet 45 having been cut off) the ink pad 46 drops back and contacts with the end of the printing die, in the position shown in Figure 6.
- 20 The operation of my machine as so far described is as follows. Lumber, either as discharged from the planer P or as delivered endwise by any suitable mechanism, drops from the level p to the level of the upper board B in the magazine 3. The first board may, because of its flexibility, tend to sag and to be obstructed by the frame members 90, and it is not desirable to provide a smooth surfaced table, because sawdust, chips, splinters, and the like may get beneath the boards and cause them to fail to register properly with the magazine parts, especially the wall 34. However, by providing inclined plates 92 upon each of the frame members 90, spaced from the adjacent frame member, the sagging end of the board will ride on these inclined plates 92, and will ultimately drop from the level p into the magazine. Its leading end will contact with the buffer member 30, provided the board has sufficient momentum when it drops from the level p . Preferably several boards are piled up in this manner before any one of them is discharged, and means to this end will be explained hereafter.
- 25
- 30
- 35
- 40
- 45
- 50
- 55

The conveyor chains 7 are then started, under manual or automatic control (as will be explained), the magazine wall 34 having been first adjusted to the proper height to permit discharge of one board only, and the lugs 72 on the several chains 7, engaging the bottom board simultaneously at spaced points,

draw this board from beneath the pile in the magazine and start it on its way edgewise along the frame members 90. Such a board is illustrated by the board B' in Figure 3. Should it stick in the opening, automatic means to be described later stops the chains.

Each board is carried past the trimming station, where are located the saws 1 and 10. The latter is fixed and trims the end of the board which was nearest the planer P. The saw 1 had been adjusted in accordance with the length of board to be operated upon, and trims the former leading end. The board continues past the saws without a stop, both saws operating simultaneously so that there is no tendency to cock the board sidewise. Another board B² follows immediately the board B', and the board B' comes opposite the printing die at 4. Suitable controls, to be explained hereafter, energize the magnet 45, and the printing die 4 starts toward the end of the board, or toward both ends if two are employed, and the freshly trimmed ends of the board are stamped with the matter prepared upon the die 4. It is not necessary to halt the movement of the board to accomplish this, since the movement of the die towards and from the board is quite rapid, and the contact is only momentary. The board then continues past the printing station and onto a grader table G, or any other suitable conveyor, where it is removed and piled. The action is entirely automatic and requires no attention, nor is any appreciable time lost in the handling of the boards between the planer and the grader table.

In order that the boards may not cock and stick in the magazine, it may be desirable to employ a jogging means, such as is illustrated at 5. This consists of a series of vertically reciprocable pins or rods, positioned so that they will engage even the most narrow board received in the magazine, supported from the frame members 90, acted upon by cams 50 carried upon a shaft 51, and operable in time with the lugs 72 to bump the bottom board in the interval between discharge of one board and pick-up of the next board. To accomplish this timing a pulley or sprocket 52 on the shaft 51 may be engaged with the chains or like members 75 which drive the chains 7, or with one of the latter chains itself.

Notwithstanding this jogger or other safeguards, occasionally a board may jam in the discharge opening beneath the wall 34. This exerts a force tending to move the wall 34 to the left, as viewed in Figure 3. To avoid damage to the machine and to the lumber, the controls effecting lateral movement or adjustment of the wall 34 are reversible when such force is applied, and the lateral force causes the wall to move out, away from the wall 33. To prevent ultimate damage, a

switch arm 63 controlling a circuit to the motor 73 which drives the chains 7, is so disposed that the circuit will be broken upon contact with the switch arm by a member 5 movable with the wall 34. Such a contact member might be positioned in many suitable places, and might assume various forms. As an illustration, I have shown a contact finger 86 on one of the shafts 83 (see Figures 10 3 and 11) positioned to engage the switch arm 63, supported on a bracket 832.

The machine would ordinarily be designed to accommodate boards from about four inches up to twelve inches in width, but for 15 some purposes it may be desirable to dispose two six-inch boards in the magazine at one time side by side. In order to prevent jamming of the rear board, engaged by the lugs 72, with the rear edge of the board in the adjacent pile and just above the level of this rear board, it will be necessary to provide a 20 slight step 93 (see Figure 4) which will slightly raise the forward board of such a pair and over which the rear board of such 25 a pair will ride, as may be observed in dotted lines in Figure 4.

It is not desirable to permit the printing dies 4 to move inward toward the position where a board should be unless there is a 30 board in place against which the dies may strike. Furthermore, it is essential that the device be timed properly to print upon boards of different widths substantially midway between the two edges. Proper controls 35 and adjustments for such purposes may be accomplished by the electrical means illustrated more or less diagrammatically in Figures 8, 9, 10, and 11, and which will presently be explained.

40 Boards fed into the magazine at different times will vary greatly in length, and the rate of removal by the lugs 72 and chains 7 must approximately correspond to the rate of delivery by the planer. The planer can deliver two twelve foot boards, comprising 45 twenty-four linear feet, in the same time required for the delivery of one twenty-four foot board, but at least two boards must be taken from the bottom of the pile in the first 50 instance, during this time, in order to prevent the pile from ultimately reaching the height of the planer bed and jamming the planer, whereas but one board needs to be removed in the second instance. The removal of two 55 boards means that the chain 7 must run at such a speed that two sets of lugs 72 pass across the magazine; the removal of one board in the same length of time requires only half the speed.

60 To a certain extent such variations can be taken care of by varying the speed of the motor. However, too great a speed of the chains will deplete the pile of boards in the magazine, and make it necessary for each 65 board to bump across the frame stringers 90

at high speed, which is not desirable. A variable speed motor will not invariably give the right speed under all conditions, hence I prefer to provide an automatic means to stop the motor 73 and chains 7 when the pile of 70 boards in the magazine has been reduced to one board, so that the continued discharge of boards from the planer will build up a pile in the magazine, and to start the motor again only when a pile of sufficient size has accumulated to run some little time without stopping—the motor being adjusted to run the chains at a speed approximately that required to remove the boards as fast as or just a trifle faster than they are supplied. 80 This automatic start-stop means may be a part of the electric arrangement, and is so illustrated in Figure 11.

The electrical controls shown in Figures 8, 9 and 10 pertain more particularly to the controls for the printing mechanism and to the adjustment of the speed of the chains 7 to correspond to the different widths of boards, so that each board may be presented at the printing point in such position, and the printing mechanism operated at such time, that the printing dies will strike approximately midway between the edge of each board. The electrical controls shown in Figure 11 pertain more especially to the control 95 of the starting and stopping of the chains 7 to compensate for a greater or lesser number of boards within the magazine.

Referring first to Figures 8, 9 and 10, current from the line is supplied to the two magnets 45 through circuits which include a timing switch. Thus a cylinder 64 of insulating material may be secured upon or driven in time with the shaft 52, and carries a strip 641 of conducting material, extending lengthwise. Held in a yoke 642 are pairs of brushes 643 and 644, and 645 and a brush complementary thereto but not shown. Thus the brush 643 and the brush 645 are similar, each in its own pair, and the brush 644, being complementary to the brush 643, has a counterpart which is complementary to the brush 645.

Considering first the brushes 643 and 644, it will be observed that current from the line, passing through a safety or cut-out switch, represented at 60, passes by a lead 646 to the brush 643, and a lead 647 returns the circuit from the brush 644 to the opposite side of the line, except as it is interrupted by a switch 61 and by the separation of the brushes or contacts 643 and 644. Assuming the switch 61 to be closed, the circuit is completed whenever the contact strip 641 passes beneath the two brushes 643 and 644, and this energizes the solenoid or magnet 62 and closes the switch 620 in the circuit 621 and the branch thereof 622, which includes the printing magnet 45. The result is, assuming the switch 61 to be closed, the printing devices are energized each time the contact strip 641 comes 115 120 125 130

around to the brushes 643 and 644. By so supporting these brushes in the yoke 642, and by providing a means to adjust this yoke angularly relative to the drum 64, the timing of this instant of contact to space the striking point of the die with relation to the face of the lugs 72, may be accomplished. This adjustment may be done by means of the arm 630, the link 631, the control handle 632, and the scale sector 633, graduated in suitable units, for instance, inches of width. As set in Figure 9, the printing device will operate upon boards of ten-inch width, the mid-point of the die striking the mid-point of the board as the latter advances.

For occasions when two boards are disposed side by side in the magazine, as shown in Figure 4, it is essential that the printing device be operated twice in rapid succession, and such boards ordinarily would be only of six-inch width. Accordingly, by providing the extra leads 648 and 649, leading respectively from the main line or the lead 646 to the brush 645, and from the brush which is complementary thereto back to the other side of the line, or to the lead 647, it is possible to effect a second actuation of the printing mechanism when the contact strip 641 passes the brush 645 and its complementary brush. In order that the double acting mechanism may be inoperative whenever there is but one board to be printed at a time, a switch 640 is provided, normally interrupting one of these leads, for instance the lead 648.

In the system as described it has been assumed that the switch 61 remained closed, and there would be no need of such a switch if it were a certainty that there would always be a board in position to print upon when the printing mechanism is energized, but such is not always the case. Adjacent the path of the boards as they are carried along the frame members 90 is an arm 610 which is engaged by the board as the latter approaches printing position. This arm, mounted upon a rock shaft 611, controls an arm 612 normally held retracted by a spring 613, but when pressed forward by engagement of the arm 610 with a board, this arm 612 depresses a button 614 to close the switch 61. Thus, until the board moves past the printing position, the switch 61 is held closed by the board itself, but if no board is in position, the switch 61 is not closed and the remainder of the circuit will not become energized.

As seen in Figure 11, the motor 73 driving the chains 7 has associated with its circuit a pair of spaced contact points 67 and 670, and also a pair of spaced contact points 671 and 672. Supported within the magazine 3, to move with the buffer 30, and for convenience supported upon an extension 321 of its supporting carriage 32, is a pivotally supported arm 322. Two such arms

may be employed, or the one arm may carry two conducting bridge members 673 and 674 adapted to close the gap, respectively, between the contacts 67 and 670, and between the contacts 671 and 672. The contacts 671 and 672 preferably are yieldingly supported, as best shown in Figure 11.

As lumber piled within the magazine 3 is depleted, there comes a time when there remains but one more board in the magazine, the parts are so adjusted that at such time the gap between the contacts 67 and 670 will be closed, and this will energize a relay in such manner as to open the circuit to the motor 73, stopping this motor and stopping the feed of the chains 7 and lugs 72. The planer will continue to deliver boards to the magazine, and though the gap between the contacts 67 and 670 is broken again, the controls are so arranged that the motor 73 will not again be energized until a considerable number of boards have been piled up in the magazine, giving enough to run on for a time, at the normal rate of accretion, without danger of stoppage of the motor. When sufficient boards have been piled up, the arm 322 is raised until the gap between the contacts 671 and 672 is closed, and these are arranged to close the circuit to the motor 73 and start the same.

To accomplish these ends, a lead 675 runs from the main line to the contact point 672, and a branch 676 runs to the contact point 670. From the contact 671 a lead 680 runs to a coil 68, controlling movement of the core 681 and the head 682 thereon. Movement of this solenoid core controls the opening and closing of a switch at 683 by means of a pivoted arm 684. When the solenoid core 681 is permitted to drop, the switch at 683 is closed, but upon raising the solenoid core 681, the switch 683 is opened. Since the switch 683 is in the circuit of the solenoid itself, this action de-energizes the solenoid, and it may be held in this position by the catch 660, controlled by movement of the core 661 under the influence of the coil 66. The coil 66 is included in a circuit 662 and 663 which runs to the motor 73 through the contact 67 and (when the gap between 67 and 670 is closed) the lead 676. The catch 660 and the head 682 likewise carry contact members 664 and 665 respectively, to which are connected the leads 666 and 686, which are directly in the motor circuit. The lead 677 comprises the other side of the motor circuit, complementary to the lead 686. The latter lead 686, or the lead 677, may be interrupted by the safety switch 63, previously referred to. A start and stop switch may be included at 65.

In the position of parts shown in Figure 11, current from the main line passes by the lead 676 to the contact 670, and when all but one of the boards in the magazine have been withdrawn, the arm 322 will drop to bridge the

gap between the contacts 670 and 67, and current will then pass by the lead 663 through the coil 66 and lead 662 back to the other side of the main line. The coil 66 will be energized, and the catch 660 will be withdrawn, breaking contact between the contacts 664 and 685, and thereby breaking the circuit to the motor 73. Withdrawal of the catch 660 permits the solenoid core 681 to drop, and this 5 closes the switch at 683, but the motor circuit is not closed thereby since there is a gap between the contacts 664 and 685. However, continued operation of the planer piles the boards higher in the magazine, until eventually 10 the arm 322 is brought high enough to bridge the gap between the contacts 671 and 672. At this time current from the main line passes by the lead 675 through the contacts 672 and 671 in turn, through the lead 680 and the coil 68, past the now closed switch 683, and thence back to the main line. In the 15 course of this, the coil 68 is energized and pulls upward the core 681, closing the circuit to the motor including the contacts 664 and 685. The switch arm 684 is thrown back, breaking the circuit at 683 through the coil 68, and the catch 660 engages and holds the head 682, whereby the motor circuit is held 20 closed. Parts have now returned or will 25 shortly return to the position of Figure 11.

What I claim as my invention is:

1. In combination, a conveyor table, means for advancing boards lengthwise and piling them upon said table, a magazine to receive 35 said boards, and to align one end thereof, means to remove the lowermost board from the magazine and to advance it edgewise over the table, a saw disposed to trim the previously aligned end of boards thus advanced, printing mechanism disposed to engage the 40 trimmed end of such boards, and means connecting the saw and printing mechanism for conjoint adjustment.

2. In combination, a conveyor table, means 45 for advancing boards lengthwise and piling them upon said table, a magazine to receive said boards, and to align one end thereof, means to remove the lowermost board from the magazine and to advance it edgewise over 50 the table, a saw disposed to trim the previously aligned end of boards thus advanced, printing mechanism disposed to engage the trimmed end of such boards, means connecting the saw and printing mechanism for conjoint adjustment, a second saw fixed in position 55 to engage and trim the opposite end of such boards, as they advance, and a second printing mechanism fixed in position to engage such latter end, following the trimming 60 operation thereon.

3. In combination with means for advancing boards lengthwise, a magazine to receive and pile said boards, and to align one end thereof, means to remove the lowermost board 65 from the magazine and to advance it edge-

wise, a saw disposed to engage and trim one end of each board, as previously aligned, as it advances, a second saw, and means supporting said second saw for adjustment lengthwise of the boards, to trim the opposite end. 70

4. In combination with means for advancing boards lengthwise, and means at a lower level to move boards edgewise, a magazine to receive boards from the first means and to pile them for delivery to the second means, comprising a wall to guide one edge of the boards, a second wall movable in a vertical plane to vary the spacing of its lower edge from the bottom of the magazine, buffer means adjustable lengthwise of the magazine to stop boards advancing into the magazine, and approximately to align them therein, and means disposed to engage and operate upon such aligned ends of boards as they advance 75 edgewise beyond the magazine. 80

5. In combination with means for advancing boards lengthwise, and a magazine to receive and pile them, buffer means to approximately align the boards as received in the magazine, comprising a weight of considerable mass, relative to the boards, an overhead support, and means suspending said weight from the overhead support. 90

6. In combination with means for advancing boards lengthwise, and a magazine to receive and pile them, buffer means to approximately align the boards as received in the magazine, comprising a weight of considerable mass, relative to the boards, an overhead support, parallel links suspending said weight from the overhead support, and means to adjust the position of the buffer means lengthwise of the magazine. 95

7. In combination, a magazine to receive and pile boards, means to advance boards lengthwise into said magazine, means at a lower level to engage the lowermost board in the magazine and to move it edgewise therefrom and beyond, a saw adjustable in the direction of the boards' length, and disposed to trim the previously leading end of a board as it now moves edgewise past the saw, and said magazine including a buffer member engageable by the leading end of the boards as they are advanced into the magazine to approximately align such ends, and means for simultaneously adjusting the buffer and saw. 100 105 110 115

8. In combination with two axially spaced saws, one fixed and the other movable towards and from the fixed saw, means to nearly align one end of each board of a pile with the plane of the movable saw, means connecting the latter means and the movable saw for like adjustment, and means to advance such boards edgewise past the saws to trim their ends. 120

9. In combination with two axially spaced saws, one fixed and the other movable towards and from the fixed saw, a magazine for receiving and piling boards, means to feed such boards lengthwise into the magazine, 125 130

means connected for movement with the movable saw, and engageable with the leading end of boards as they are fed into the magazine to approximately align one end of each board with the plane of the movable saw, and means to advance such boards edgewise from said magazine past the saws to trim their ends.

Signed at Tacoma, Pierce County, Washington, this 11th day of January 1932.
